MEANS FOR REMOVABLY SECURING THE
HEADS OF METAL CONTAINERS

Louis B. Wackman, St. Louis, Mo.

Application February 19, 1938, Serial No. 191,395

1 Claim. (Cl. 220—61)

This invention relates to the means for removably securing the heads of metal containers and the like, and specifically relates solely to the removable head securing means such as is used to secure and provide a fluid tight relation between the body of the container and its head.

The principal object therefore of the invention is to provide the clamping or locking ring with improved relatable clamping means.

Another object is to provide the clamping means with features for retaining it on the ring whether or not the ring is assembled or disassembled.

A further object is to provide the clamping means for the ring with means for improved wire sealing cooperation with the ring.

Other objects and advantages will appear as this description progresses and by reference to the drawing, in which:—

20 Figure 1 is a plan view of an embodiment of the invention showing its application to the head of a container for securing and locking the head to the chime or rim.

Figure 2 is an enlarged fragmentary elevation taken in the direction of the arrow 2.

Figure 3 is an enlarged vertical fragmentary sectional elevation taken approximately on the line 3—3 of Fig. 2.

Figure 4 is an enlarged fragmentary side elevation of one of the ring ends.

Referring by numerals to the accompanying drawing, 5 designates a locking ring which is split, as shown at 6, to provide adjacent ends 7 and 8, the ring end 7 having an enlarged portion 9 and the ring end 8 having an enlarged portion 10.

Depending from the portion 9 is a strap-like part 11 having a cylindrical bearing block 12 formed by curling the part 11 on its extending end and in which a horizontally extending bore or opening 13 is formed as a result of the curling. Mounted in the opening 13 is the bearing portion 14 of a horizontally turnable member 15, and formed or mounted on one end of the bearing portion 14 is a head or shoulder 16 having a slot 17 for turning tool engagement, said head adapted to bear against the end 18 of the bearing block 12. For engagement against the end 19 of the bearing block 12, is a shoulder or collar 20, and formed in the head 16 and the shoulder 20 are respective right angularly disposed openings 21 for sealing wire engagement.

The turnable member 15 outwardly of the shoulder 20 is threaded, as designated at 22, for cooperation with the threaded opening 23 in the

bearing block 24 which is depended from the portion 9 on the end 8 of the ring 5.

The metal container or barrel to which this improved locking ring 5 is applicable, is formed at the open end to which the removable head 25 is applied, with an outwardly projecting bead 26, the head 25 having a rim 27 of concavo-convex form, fitting over the bead 26 on a gasket 28 which is carried on the underside of the rim 27.

For securing the locking ring 5 over the rim 27 of the head 25 to provide a fluid tight relation with the bead 26 of the container, the ring 5 which is of a charnel shape in cross section is expanded, and is positioned and mounted in a manner so that the top side 29 of the ring will engage the rim 27 of the head 25, and the bottom side 30 of the ring is engaged against a lower portion of the bead 26 and the ends 7 and 8 of the ring 5 are positioned to aline the threaded portion 22 of the member 15 with the threads 23 of the bearing block 24, and a turning tool is then engaged in the slot 17 of the head 16 of the member 15, and said member when turned, will draw the ends 7 and 8 of the ring 5 towards each other for contracting the ring in drawing the rim 27 of the head 25 in compressing engagement with the gasket 28.

When the ring 5 has been sufficiently contracted to provide a fluid tight relation between the head and the container, a sealing wire 31 is passed through respective openings 21 of the head 16 and shoulder 20 of the turnable member 15 and looped and secured by the seal 32. Any attempt to gain unauthorized access to the container by reverse turning of the member 15, will cause the seal wire 21 to be broken, thus indicating tampering.

Upon expanding the locking ring 5 for its removal, it is to be noted that after the ends 7 and 8 of the ring have been disconnected from one another, the turnable member 15 will be retained by the ring end 7 as shown in Fig. 4, so that it cannot become separated and mislaid, thus providing a self-contained and complete locking ring.

Due to the circular shape of the locking ring 5 and to assist alining the turnable member 15 for threaded engagement with the threaded bearing block 24, the bore or opening 13 in the bearing block 12 is enlarged, to allow lateral movement to be given to the member 15.

While a preferred embodiment of the invention is shown, it is to be understood that various changes, size, shape and arrangements of parts, may be resorted to without departing from the

spirit and scope of the invention of the claim hereto.

What I claim is:

5 A split locking ring for securing heads to containers, said locking ring having an integral depending part at each end curled to form cylindrical sleeves, one of said sleeves being interiorly threaded, and a turnable member having one end journaled in the other sleeve and having its

other end threaded for cooperation with the threaded sleeve to draw the ends of the locking ring together, said turnable member having a pair of spaced shoulders positioned at opposite ends of the sleeve in which it is journaled for abutment 5 with respective ends of the sleeve to retain said turnable member in said sleeve.

LOUIS B. WACKMAN.
